DESIGN FOR A HANDBAG

Samuel Nathan, Allentown, Pa.

Application June 1, 1939, Serial No. 85,293

Term of patent 3½ years

To all whom it may concern:

Be it known that I, Samuel Nathan, a citizen of the United States of America, residing in Allentown, county of Lehigh and State of Pennsylvania, have invented a new, original, and ornamental Design for a Handbag, of which the following is a specification, reference being had to the accompanying drawing, forming part thereof, wherein,

The lining on the handles and back of the pocket represents grosgrain ribbon.

I claim:

The ornamental design for a handbag, substantially as shown and described.

SAMUEL NATHAN.
